UNITED STATES PATENT OFFICE

172,739

GUIDED MISSILE

Willis J. Benckert, Baltimore, and John D. Bitner,
Jr., Towson, Md., assignors to The Glenn L.
Martin Company, Middle River, Md., a corpo-
ration of Maryland

Application February 20, 1952, Serial No. 18,610

Term of patent 14 years

(Cl. D71—1)

To all whom it may concern:

Be it known that we, Willis J. Benckert and John D. Bitner, Jr., citizens of the United States of America, and residents, respectively, of city of Baltimore, State of Maryland, and Towson, county of Baltimore, State of Maryland, have invented a new, original, and ornamental Design for a Guided Missile, of which the following is a specification, reference being had to the accompanying drawings, forming a part thereof.

Figure 1 is a bottom perspective view of the missile in flight, showing the configuration of the air intake duct.

Figure 2 is a top perspective view of the missile.
Figure 3 is a front elevational view thereof.

Figure 4 is a side elevational view of the sub-
ject missile and

Figure 5 is a top plan view thereof.

We claim:

The ornamental design for a guided missile,
substantially as shown.
